[57] CLAIM

The ornamental design for a secure monitor housing, as shown and described.

DESCRIPTION

FIG. 1 is an enlarged top front and right side perspective view of a secure monitor housing showing our new design;

FIG. 2 is a right side elevational view thereof the opposite side being identical in appearance;

FIG. 3 is a front elevational view thereof;

FIG. 4 is a top plan view thereof;

FIG. 5 is a back elevational view thereof; and,

FIG. 6 is a bottom plan view thereof.

The circular pattern is partially shown in the figures for ease of illustration and it is understood to continue uniformly across each of the indicated surfaces.

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 341, 358
DATED : November 16, 1993
INVENTOR(S) : Stolz et al.

It is certified that error appears in the above-identified patent and that said Letters Patent is hereby corrected as shown below:

In the title page, item [75] Inventors, please delete " Howard Stolz " and insert
-- Howard W. Stolz --.
